UNITED STATES PATENT OFFICE

WILLIAM L. BRUNING, OF NEW YORK, N. Y., ASSIGNOR TO BROWN & BIGELOW, OF ST. PAUL, MINNESOTA, A CORPORATION OF MINNESOTA

DESIGN FOR A DECK OF PLAYING CARDS

Application filed October 21, 1932. Serial No. 45,437. Term of patent 3½ years.

To all whom it may concern:

Be it known that I, WILLIAM L. BRUNING, a citizen of the United States, residing in New York city, in the county of New York, and State of New York, have invented a new and original Design for a Deck of Playing Cards, of which the following is a specification, reference being had to the accompanying drawing, forming a part thereof.

The drawing illustrates face views of the picture cards, the Joker, and the Ace of

Spades. The ornamentation upon the faces of these cards is the dominant feature of the design, the remaining cards of the deck being conventional.

I claim:

The ornamental design for a deck of playing cards as shown and described.

In testimony whereof, I have signed this specification at New York city, New York, Sept. 27, 1932.

WILLIAM L. BRUNING.
